PHONOGRAPH

Michael J. Di Toro, East Orange, N. J., assignor
to Thomas A. Edison, Incorporated, West Orange, N. J., a corporation of New Jersey

Application October 3, 1939, Serial No. 297,643

13 Claims. (Cl. 179—100.4)

This invention relates to phonographs, and more particularly to phonographs having sound-translating systems involving amplification between their pick-up and output points. The invention is especially concerned with phonographs which are intermittently operated—i. e., phonographs in which the operation is frequently suspended during the use of the machines—as for example, commercial phonographs or dictating machines such as are used for the recordation and reproduction of dictation, conferences, and the like.

Recording and reproducing phonographs having amplifying sound-translating systems typically employ, as a source of pick-up, a sound transmitter or phonographic reproducer and, as a source of output, a phonographic recorder or sound receiver, these pick-up and output sources being interconnected by an oscillation-transmitting channel serially including means for amplifying electrical oscillations. Typical forms of the sound transmitter and sound receiver are the microphone and loudspeaker, respectively, and of the phonographic recorder and reproducer are the electro-mechanical translating devices selectively adaptable to convert electrical oscillations into corresponding vibrations of a record-cooperating stylus, or vice versa. In operating the machine, the phonographic recorder or reproducer is placed into operative relationship with the record, depending on whether sound recordation or sound reproduction is to be effected, and a relative progressive movement is effected between the record and the recorder or reproducer. Such relative movement between the record and the recorder will cause a groove to be progressively cut or impressed in and along the surface of the record having modulations corresponding to the electrical oscillations fed into the recorder; and a tracking movement of the reproducer, as along a modulated groove on the record, will cause electrical oscillations to be created in correspondence with the modulations of the groove. While I herein illustrate my invention in connection with a phonograph of the combined recording and reproducing type having pick-up and output sources of the form above represented as typical, it will be understood that my invention is applicable to phonographs which are restricted in use to either recording or reproducing and that the particular form of the pick-up and output sources of the sound-translating system is not necessarily important to my invention.

In order that the recordation and reproduction

of sound may be effected with good fidelity it is necessary, among other things, that extraneous excitations of the sound translating system be of a low order. Such extraneous excitations may be caused as an incident of the starting and stopping of the machine. This source of extraneous excitation is of especial importance in commercial phonographs since such phonographs are frequently suspended in operation during their use by means of electrically actuated clutch mechanisms. These mechanisms generally produce noise, vibration and electrical disturbance of an order which may be picked up by the sound-translating system—particularly in sound-translating systems involving amplification between its points of pick-up and output. For example, during the operation of recording this vibration and noise may be picked up by the microphone and the electrical disturbance by the amplifier to cause extraneous recordations on the record; and during a suspension in recording, heavy room noises and vibrations may be picked up by the microphone to actuate the recorder and thereby cause further extraneous recordations, in the form of indentations, on the record. During reproducing, the vibration and electrical disturbances accompanying the starting and stopping of the machine may be picked up by the reproducer and amplifier, respectively, to cause the emission of disturbing sounds. Also, during a time of suspensions in reproducing, amplifier hum and vibration of the machine may cause disturbing sounds to be emitted to distract the operators' attention from their work. Thus in machines wherein the recording and reproducing operations involve frequent transitional conditions of starting and stopping the fidelity of the reproduced sound and the convenience of operation of the machine may be greatly impaired.

It is an object of my invention to suppress or eliminate in phonograph systems, the recordation and/or reproduction of extraneous matter.

It is another object of my invention to provide simple means in a phonograph for obviating such difficulties as are above mentioned.

Another object of my invention is to improve the fidelity, and the convenience, of operation of a phonograph—particularly phonographs which are frequently suspended in operation during their use.

It is another object of my invention to concurrently control both the mechanical and sound-translating systems of a phonograph.

Another object of my invention is to provide

in a phonograph having mechanical and sound-translating systems, automatically operated means for controlling one of such systems as an incident of controlling the other.

Another object of my invention is to prevent suspensions in the operation of a phonograph from causing extraneous excitations of its amplifying sound-translating system.

A feature of my invention is to cause the sound-translating system of a phonograph to be rendered operative and inoperative as an incident of the starting and stopping of the mechanical operation of the machine.

Another feature of my invention is to cause the operative and inoperative conditions of the sound-translating system to be effected as terminal and initial incidents of the starting and stopping of the mechanical operation of the machine.

Other and allied objects and features of my invention will more fully appear from the following description and the appended claims.

In the description of my invention reference is had to the accompanying drawing which shows, largely in diagrammatic form, mechanism and circuits of a recording and reproducing phonograph embodying my invention.

The phonograph shown in the accompanying drawing comprises a mandrel 1 adapted to serve as a support for a cylindrical record 2 and having a shaft journalled in a standard of a frame 5 of the phonograph. Rotation of the mandrel is effected by an operating mechanism suitably comprising an electrical motor M coupled, as by a belt 6, to a drive pulley 7. The starting and stopping of rotation of the mandrel is preferably controlled by a clutch 8 interposed between the drive pulley 7 and the mandrel shaft. This clutch comprises a toothed clutch member 9 on the pulley 7 and another toothed clutch member 10 which is splined to the mandrel shaft for movement into and out of engagement with the clutch member 9, the splining being effected by a pin and slot connection of which the pin appears as 10". Movement of the clutch member 10 is effected by an actuating mechanism 12 which is coupled to the clutch member by way of a vertically disposed clutch lever 13. This clutch lever is pivoted, as at 14, to the frame 5 and is coupled, at its upper end, to the clutch member 10 by means of a pin 15 on the lever which slidably engages an annular groove 10' in the clutch member. Pivoted to the lower end portion of the clutch lever, by a pin 16, is a link 17 which serves to connect the clutch lever to the actuating mechanism 12.

The actuating mechanism 12 is preferably of a construction such as is disclosed in Langley Patent No. 1,380,480, issued June 7, 1921, and entitled "Controlling device." A mechanism of this construction comprises two electromagnets 18 and 19 respectively operating pivoted armatures 20 and 21 of which the armature 20 is pivotally connected, by a pin 17', to the link 17. The armatures 20 and 21 respectively carry cams 20' and 21' which are resiliently held in coacting relationship by means of a tension spring 22 connected between the armatures. When one of the armatures is actuated the other armature is maintained in a locked condition by means of the coacting cams 20' and 21'; however, when the actuated armature reaches the end of its travel the other armature is released from its locked condition and is then moved, by the spring 22, towards the other armature and into a position for subse-

quent actuation. When the armature, which was unactuated in the above operation, is next actuated this process is reversed.

In operation the electromagnets 18 and 19 are alternately energized and their circuits are automatically broken as an incident of the completion of actuation of their respective armatures. The means for automatically breaking the circuits of the electromagnets comprises a pivoted arm 23 interposed between the armatures and carrying a vibration and sound absorbing pad 24 which fits the inner sides of the armatures when the armatures are in leftward and rightward positions. Connected to the arm 23 is a switch arm 25 which is adapted to alternately make connection with contact members 26 and 27, which contact members are respectively serially included in the circuits of the electromagnets 19 and 18. When the armatures 20 and 21 are in their leftward positions, as shown, the switch arm 25 makes connection with the contact member 26, thereby causing the circuit of the electromagnet 19 to be prepared for operation. When a current is passed through the circuit of this electromagnet the armature 21 is actuated in a rightward direction. At the completion of this actuation of the armature 21 the armature 20 is moved, in response to the spring 22, towards the other. As the armature 20 is so moved it rocks the pivoted arm 23 and in its terminal movement engages the clutch 8. The initial rocking movement of the pivoted arm 23 causes the switch arm to break connection with the contact member 26, thereby breaking the circuit of the electromagnet 19; and the terminal rocking movement of the arm 23 causes the switch arm 25 to make connection with the contact member 27, thereby preparing the circuit of the electromagnet 18 for operation. When a current is passed through the circuit of the electromagnet 18 the above process is reversed: the armature 20 being actuated leftwardly to first disengage the clutch and to then release the armature 21, and the armature 21 being then moved towards the other, in response to the spring 22, to cause first a breaking of the circuit of the electromagnet 18 and thereafter a preparation of the circuit of the electromagnet 19 for reoperation.

The alternate energizing of the electromagnets 18 and 19 is manually controlled by means of a single-pole double-throw hand switch 28 having a pole member 29 normally making connection with a contact member 30, as by a biasing of the pole member, and movable to break connection with the contact member 30 and to thereafter make connection with a contact member 31. The pole member 29 of the hand switch 28 and the switch arm 25 of the actuating mechanism 12 are connected by respective conductors 32 and 33 to the leads of a two-wire cable 34 which is adapted to make connection with a suitable source of power as by way of a plug 35. The contact members 30 and 31 of the hand switch 28 are respectively connected, by the conductors 36 and 37, to the electromagnets 18 and 19, the connection to the electromagnets being made on the sides opposite to those making connection with the contact members 27 and 26. By this arrangement the electromagnet 19 is energized to cause the engagement of the clutch 8 as the pole member 29 of the hand switch 28 is moved into start position—the position of the pole member when it makes connection with the contact member 31—and the electromagnet 18 is energized to cause the disengagement of the clutch as the pole

member 28 is moved into stop position—the position of the pole member when it makes connection with the contact member 30. However, these energizings of the electromagnets 18 and 19 are only momentary by reason of the automatic breaking of the circuits of the electromagnets as above explained.

The sound-translating system for the phonograph comprises an electro-mechanical translating device 38 of a type selectively placeable into inoperative condition and respective operative conditions for recording and reproducing, an electro-acoustical unit 39 comprising a microphone 40 and loud-speaker 41, an electrical amplifier 42 which receives its power by way of a cable 43 connected with the cable 34, and an oscillation-transmitting channel which includes a multiple switch 44 selectively operable to connect the translating device 38 and electro-acoustical unit 39 to the amplifier in a manner to condition the sound-translating system for recording or reproducing. It will be further understood that while it is preferred, in a recording and reproducing phonograph, to have the microphone 40 and loud-speaker 41, and the electro-mechanical translating means, each in the form of a unitary structure, as shown, the microphone and loud-speaker may be mechanically separate and the translating means may constitute separate recording and reproducing devices.

During the operation of the machine a relative progressive movement is effected between the translating device 38 and the record. In the present instance this movement is effected by a rotation of the mandrel 1 and a concomitant feeding of the translating device along the record as by means of a rotatable feed screw 11 which is engaged by a feed nut 38' carried by the translating device 38 and which is rotatably coupled to the mandrel shaft by a train of gears 11'. The starting and stopping of this relative progressive movement, to render the phonograph mechanically operative and inoperative, is controlled by the clutch 8 which in turn is controlled by the hand switch 28, as heretofore described.

The sound translating device 38 is of a form which, when conditioned for recording, will receive sound representing oscillations by way of a pair of terminals 45 and impart an undulating movement in accordance with such oscillations to a recorder stylus 46; and which, when conditioned for reproducing, will create electrical oscillations in accordance with an undulating movement imparted to a reproducer stylus 47. The conditioning of the translating device is controlled by a lever 48. The control effected by this lever is such that when the lever is in a leftward or recording position, the recorder stylus is maintained in operative relationship with the record and the translating device is in a condition for recording; that when the lever is in a rightward or reproducing position, the reproducer stylus is maintained in operative relationship with the record and the translating device is in a condition for reproducing; and that when the lever is in a neutral or inoperative position the recorder and reproducer styli are each held free of the record to place the translating device into inoperative condition.

The conditioning of the sound-translating system for recording and reproducing involves both a conditioning of the translating device 38 and a proper connecting, by the switch 44, of the translating device 38 and electro-acoustical 75

unit 39 to the amplifier 42. In order that the state or condition of the sound-translating system may be controlled by a unitary means the lever 48 is connected to a bar 50, which controls pole members 51, 52 and 53 of the switch, by means of a suitable link 49. The pole member 51 serves as the pole of a single-pole double-throw switch having left and right contact members 51' and 51'', whereas the pole members 52 and 53 serve as poles for single-pole single-throw switches respectively having contact members 52' and 53'. When the lever 48 is moved leftwardly into recording position the pole members 51 and 52 make connection with the contact members 51' and 51'' respectively; when the lever 48 is moved into reproducing position the pole members 51 and 53 make connection with the contact members 51'' and 53' respectively; and when the lever 48 is in neutral position each of the pole members are out of contact with their associated contact members.

The amplifier 42 is provided with both high and low impedance inputs and outputs, the high and low impedance inputs being respectively obtained from terminals 54 to 55 to ground terminal 56 and the high and low impedance outputs being respectively obtained from terminals 57 and 58 to ground terminal 59. The microphone is adapted to work into the high impedance input of the amplifier and the high impedance output of the amplifier to feed into the translating device 38 when the translating system is conditioned for recording, and the translating device 38 is adapted to feed into the low impedance input of the amplifier and the low impedance output of the amplifier to feed into the loud-speaker 40 when the sound-translating system is conditioned for reproducing. In order that these connections will be made by the movement of the lever 48 into recording and reproducing positions one side of the translating device 38, microphone 40, and loud-speaker 41, respectively, is connected to ground, the ground connection of the translating device being made as at 60 and the ground connection of the microphone and loud-speaker being made as at 61. The other sides of the translating device, microphone and loud-speaker are respectively connected by the respective conductors 62, 63 and 64 to the pole members 51, 52 and 53 of the multiple switch 44; the input terminals 54 and 55 of the amplifier are respectively connected by the conductors 65 and 66 to the contact members 52' and 51'' of the multiple switch; and the output terminals 57 and 58 of the amplifier 55 are respectively connected by the conductor 67 and 68 to the contact members 51' and 53' of the multiple switch. Thus when the lever 48 is in recording position the microphone 40 is connected to the high impedance input of the amplifier by way of the pole member 52 and contact member 52' of the multiple switch, and the high impedance output of the amplifier is connected to the translating device 38 by way of the contact member 51' and pole member 51; and when the lever 48 is in reproducing position the translating device is connected to the low impedance input of the amplifier by way of the pole member 51 and contact member 51'' and the low impedance output of the amplifier is connected to the loud-speaker 41 by way of the contact member 53' and pole member 53.

During the operation of recording dictation the operator frequently suspends the operation of the machine—i. e., renders the machine me-

chanically inoperative—so as to give him time to determine the course of his thoughts, and he may also momentarily suspend the operation of the machine as an incident of listening-back on previously recorded matter for the purpose of picking up thoughts which may have escaped his mind. Also during the transcribing of a record the operator intermittently suspends the operation of the machine to permit the typing of portions of reproduced matter. Such suspensions in the operation of the machine—which are effected by the clutch actuating mechanism 12 and controlled by the hand switch 28—may cause extraneous excitations of the sound-translating system, as from the noise and vibration of the clutch 8 and actuating mechanism 12 and from the electrical disturbances created by the circuit breaking of the actuating mechanism; and during suspensions in operation of the machine, the sound-translating system may be extraneously excited by room noises and vibrations when the machine is conditioned for recording, and by motor vibration and amplifier hum when the machine is conditioned for reproducing, as heretofore explained. The terminal effect of all such extraneous excitations of the sound-translating system is to cause the fidelity of sound reproductions to be marred by the presence of peculiar and disturbing reproduced sounds, and to cause during suspensions in sound reproducing the emission of noises which distract the operators' attention from their work.

In accordance with my invention I suppress the recordation and reproduction of extraneous matter caused incidental to a suspension in operation of the machine, by placing the sound-translating system automatically into inoperative condition upon the stopping of the mechanical operation of the machine and by restoring the sound-translating system automatically to operative condition by the restarting of the machine. The placing of the sound-translating system into inoperative condition may be effected in various ways, a particularly simple method being in shorting the output of the amplifier 42 to render the amplifier inoperative, or what is the equivalent, in shorting the oscillation-transmitting channel which serves to operatively interconnect the translating device 39 and the electro-acoustical unit 39. The means for shorting the output of the amplifier comprises a switch 69 having a pole member 70 connected, as at 71, to ground and a contact member 72 connected, by a conductor 73, to the conductor 67. The switch 69 is biased to be normally closed, the biasing being effected by a spring 74 operating on the pole member 70. Opening of the switch 69 is effected as an incident of the engagement of the clutch 8 by the impingement of a stud 75, carried by the clutch lever 13, against the pole member 70 of the switch, the stud 75 being threaded into a lug 76 on the clutch lever 13 and being held in place by a lock nut 77. Thus, as the clutch 8 is engaged and disengaged, to start and stop the mechanical operation of the machine, the switch 69 is opened and closed to respectively render the sound-translating system operative and inoperative.

By an adjustment of the stud 75 relative to the lug 76 the timing of the opening and closing of the switch 69 relative to the engagement and disengagement of the clutch 8 is controlled. In accordance with my invention this timing is arranged so that the switch 69 will be opened by the terminal movement of the clutch lever 13 in

the engagement of the clutch and closed by the initial movement of the clutch lever 13 in the disengagement of the clutch. By so controlling the opening and closing of the switch 69 the sound-translating system is rendered operative concurrently with the starting of record rotation, and is rendered inoperative concurrently with the disconnection of the mandrel from its rotating means. An important result in placing the sound-translating system into inoperative condition concurrently with the disconnection of the mandrel from its driving means is that it prevents any recordation during the time the mandrel is coasting to a stop.

It has been seen, as heretofore described, that the circuit of the electromagnet 18 is broken prior to the engagement of the clutch 8 and that the circuit of the electromagnet 19 is broken subsequently to the disengagement of the clutch.

By controlling the timing of the opening and closing of the switch 69 so that the operative and inoperative conditions are effected as terminal and initial incidents of the starting and stopping of record rotation, the sound-translating system is not rendered operative until after the circuit breaking which is incidental to record starting has occurred, and is rendered inoperative before the circuit breaking which is incidental to record stopping has occurred. Thus electrical disturbances caused by the circuit breaking of the electromagnets 18 and 19 incidental to the starting and stopping of the mechanical operation of the machine is prevented from exciting the sound translating system.

Although I have herein shown and described one embodiment of my invention it will be understood that this embodiment is illustrative of my invention and not limitative thereof since the embodiment herein shown is subject to many changes and modifications without departure from the scope of my invention, which I undertake to express according to the following claims.

I claim:

1. In a phonograph having a rotatable record support, a record-cooperating phonographic translating device and means for effecting a relative progressive movement between said device and said support: the combination of an amplifying sound-translating system including said phonographic translating device, an electro-acoustical translating device, and an oscillation-transmitting channel for interconnecting said devices; a clutch associated with said movement-effecting means and operable to place the same into and out of operative condition; means for placing said sound-translating system into and out of condition whereby one of said devices is ineffective to feed the other; and means for causing said last-mentioned means to be controlled by said clutch.

2. In a phonograph having a rotatable record support, a record-cooperating phonographic translating device and means for effecting a relative movement between said device and said support: the combination of a sound-translating system including said phonographic translating device and a circuit for transmitting sound-representing oscillations to and from said device; control means for placing said movement-effecting means into and out of operative condition; a switch in said oscillation-transmitting circuit, for placing said sound translating system into and out of operative condition; and an operative coupling between said control means and said

switch for causing an operation of one by the other.

3. In a phonograph having a rotatable record support, an electro-mechanical translating device adapted to cooperate with a supported record and means for effecting a relative movement between said device and said support: the combination of a sound-translating system including said translating device, electro-acoustical means, and an electrical oscillation-transmitting circuit for interconnecting said translating device and electro-acoustical means; a clutch operable into start and stop positions to place said movement-effecting means into operative and inoperative conditions; an electric circuit-controlling switch in said circuit operable to render said sound-translating system operative and inoperative; and means, operatively connecting said clutch and said switch, for causing said sound-translating system to be rendered operative and inoperative as an incident of operating said clutch into start and stop positions.

4. In a phonograph having a rotatable support for a record, a phonographic translating device selectively conditionable for recording and reproducing a sound-representing source of electrical oscillations, a sound receiver and means for causing a relative progressive movement between said translating device and said support: the combination of a transmission means including a transmission circuit and switch means selectively operable to connect said translating device with said electrical oscillation source or to connect said translating device with said sound receiver; control means operable into start and stop positions to render said movement-causing means effective and ineffective; and a switch associated with said transmission circuit and operatively connected with said control means, for causing said transmission means to be respectively placed into operative and inoperative conditions upon the moving of said control means into start and stop positions.

5. In a phonograph having a rotatable record support and means for rotating said support; the combination of an electro-mechanical translating device selectively conditionable for recording and reproducing; electro-acoustical means including a microphone and a sound receiver; an oscillation-amplifying channel; a state-controlling means for the phonograph comprising conditioning means for said translating device and switch means associated with said channel and operated concurrently with said conditioning means, said switch means being arranged to cause said translating device to be operatively connected with said microphone when the translating device is conditioned for recording and to cause the translating device to be operatively connected with said sound receiver when the translating device is conditioned for reproducing; a control mechanism operable to start and stop rotation of said record support; and a switch, associated with said channel and controlled by said control mechanism, for causing said channel to be placed into operative and inoperative conditions concurrently with starting and stopping of rotation of said record support.

6. In a phonograph having a rotatable support for a record, a phonographic translating device operatively associated with a supported record and means for effecting a relative progressive movement between said translating device and said support: the combination of an oscillation-transmitting circuit connected with said device;

control means movable into stop position to render said movement-effecting means inoperative; and shorting means in said circuit and operatively connected with said control means for causing the circuit to be shorted by the movement of the control means into stop position.

7. In a phonograph having a rotatable support for a record, a phonographic translating device adapted to cooperate with a record on said support and means for effecting a relative progressive movement between said device and said support: the combination of an oscillation transmitting circuit connected with said translating device; control means movable into start and stop positions to render said movement-effecting means operative and inoperative; a switch differentially operable to render said transmitting circuit operative and inoperative; and means for causing a differential operation of said switch by the movement of said control means into its start and stop positions, including adjustable means for controlling the time of operation of the switch relative to the movement of said control means between its said positions.

8. In a phonograph having a rotatable support for a record, a record-cooperating translating device and drive means for effecting a relative progressive movement between said translating device and said support: the combination of means for amplifying the oscillations fed into and/or from said translating device; control means operable to start and stop the said relative movement effected by said drive means; and means operatively connected with said control means and associated with the audio channel of said amplifying means for causing the amplifying means to be placed into and out of operating condition concurrently with the starting and stopping of the mechanical operation of the machine.

9. In a phonograph having a rotatable support for a record, a sound-translating device operatively associated with a record on said support and an operating mechanism for effecting a relative progressive movement between said translating device and said support: the combination of an oscillation-transmitting channel for said device serially including an electrical amplifier provided with input and output pairs of terminals; control means associated with said operating mechanism and operable to render the same operative and inoperative; and means controlled by said control means for placing a short across and removing the same from one of said pairs of terminals as an incident of rendering said mechanism inoperative and operative.

10. In a phonograph having a rotatable support for a record and an operating mechanism: the combination of a sound-translating system comprising a phonographic translating device placeable into operative relationship with the record, an electro-acoustical translating device, and means for amplifying electrical oscillations interposed between said devices and having operative and inoperative conditions; control means associated with said operating mechanism and operable to start a relative progressive movement between said translating device and the record, and comprising an electrically operated clutch mechanism adapted to break its own circuit incidental to its operation; and means, controlled by said control means and operated incidental to the starting of said relative movement and subsequent to the breaking of the circuit of said

clutch mechanism, for causing said amplifier to be placed into operative condition.

11. In a phonograph having a rotatable support for a record and an operating mechanism: the combination of a sound-translating system comprising a phonographic translating device placeable into operative relationship with the record, an electro-acoustical translating device, and an electrical amplifier interposed between said devices and having operative and inoperative conditions; coupling means associated with said operating mechanism for causing a relative progressive movement between said translating device and the record, said coupling means comprising an electrically operated clutch mechanism operable to stop said relative movement and adapted to break its own circuit incidental to its operation; and means, operatively connected with said clutch mechanism and operated incidental to the stopping of said relative movement and prior to the breaking of the circuit of the clutch mechanism, for causing said amplifier to be placed into inoperative condition.

12. In a phonograph having a rotatable record support, a record-cooperating translating device and a drive mechanism for effecting a relative movement between said device and said support: the combination of an oscillation amplifier associated with said device; a control device associated with said drive mechanism and electrically actuatable into start and stop positions to render the drive mechanism effective and ineffective, said control device being adapted to automatically break its own circuit just prior to the same

reaching start position and just subsequent to the same reaching stop position; and means controlled by said control device to cause said amplifier to be placed into operative condition as a terminal incident of the actuation of said control device into start position and to be placed into inoperative condition as an initial incident of the actuation of said control device into stop position, whereby to cause said amplifier to be in inoperative condition at the instant of each breaking of the circuit of said control device.

13. In a phonograph having a rotatable support for a record and an operating mechanism: the combination of an amplifying sound-translating system including a phonographic translating device adapted to cooperate with the record; coupling means associated with said operating mechanism for causing a relative progressive movement between said translating device and the record, said coupling means including a clutch engageable and disengageable to start and stop said relative movement; an actuating mechanism for operating said clutch having power-supplying circuit means and switch means automatically controlled to break said circuit means coincidentally with the initial engaging movement and the terminal disengaging movement of said clutch; and means, controlled by said actuating mechanism and operated coincidentally with the terminal engaging movement and the initial disengaging movement of said clutch, for respectively placing said sound-translating system into operative and inoperative conditions.

MICHAEL J. DI TORO.
